UNITED STATES PATENT OFFICE.

WALTER HERZFELDT, OF WEYAUWEGA, WISCONSIN.

FOLDING CRATE.

1,080,553.

Specification of Letters Patent.

Patented Dec. 9, 1913.

Application filed February 10, 1913. Serial No. 747,552.

To all whom it may concern:

Be it known that I, WALTER HERZFELDT, a citizen of the United States, residing at Weyauwega, in the county of Waupaca and State of Wisconsin, and whose post-office address is Box 78, Weyauwega, Wisconsin, have invented certain new and useful Improvements in Folding Crates, of which the following is a specification, reference being had to the accompanying drawings.

This invention comprehends certain new and useful improvements in crates and relates more specifically to folding crates.

An object of the invention is to provide a folding crate which will be of extremely simple construction and which will have the parts connected in such manner that when the crate is in set up condition the parts will be securely connected and spreading of the crate will be prevented.

Another object is to provide a crate of this type with the parts connected in such manner that they may be readily folded upon one another in compact form for storing, shipping and like purposes.

Another object is to generally improve and simplify the construction of devices of this character and thereby increase the efficiency and commercial value of the same.

With the above and other objects in view, this invention consists in novel details of construction, arrangement and combination of parts, as will be hereinafter referred to in the drawings and more particularly pointed out in the specification and claims.

In the accompanying drawings forming a part of this application, Figure 1, is a bottom plan view of the folding crate, showing the same in open position, previously to folding the parts one upon another. Fig. 2, is a view similar to Fig. 1, showing the inner faces of the members. Fig. 3, is a vertical longitudinal section through the crate in set up or closed position. Fig. 4, is an enlarged detail cross sectional view through the bottom of the crate, said view being taken on the line 4-4 of Fig. 1. Fig. 5, is a detail view of the means for locking the crate in closed or set up position. Fig. 6, is an end elevational view of one of the side members of the crate. Fig. 7, is a similar view of the bottom member. Fig. 8, is a corresponding view of the top member of the crate. Fig. 9, is a like view of the other side member.

Referring more specifically to the draw-

ings, in which like reference characters designate similar parts throughout the several views, 1 designates the bottom of the crate which has riveted upon opposite sides the transversely positioned metallic bracing strips 2 and 3, the bracing strips 2 being positioned upon the upper face of the bottom 1 while the strips 3 are positioned upon the under face of said bottom, the strips 2 and 3 being opposite one another and adjacent the opposite ends of the bottom 1 and secured in position by the rivets 4, each rivet extending through a strip 2 and the strip 3 directly opposite said strip 2. The strips 2 and 3 are provided adjacent their ends with registering openings 5 which also extend through the bottom 1, and the purpose of these openings will presently appear.

The strips 3 upon the lower face of the bottom 1 are provided with the downwardly directed lugs 6 which serve as feet to support the bottom 1 above the floor or other surface upon which the crate is positioned. The opposite ends of the strips 2 upon the upper face of the bottom 1 are bent upwardly at about right angles, as shown at 7 to prevent outward movement of the lower edges of the sides of the crate, as will be later clearly understood. The strips 2 are also provided with the lateral projections 8 extending toward the ends of the bottom 1 and having their outer edges turned, as shown at 9 to receive hinge pins 10 carried by the projections 11 formed on the lower ends of the bracing strips 12 on the inner faces of the crate ends 13. It will be understood that the central portions of the turned edges 9 are cut-away to receive the projections 11, forming the other portions of the hinge by means of which the crate ends 13 are hinged to the bottom 1.

The strips 12 are secured vertically to the outer faces of the crate ends 13, by means of the rivets 14 which also secure the strips 15 to the inner faces of the crate ends 13. Screw eyes 16 or the like are secured to the inner face of the crate ends 13, near the opposite corners thereof to receive the hooks 17 carried by the crate sides 18 and 19.

The crate sides 18 and 19 are adapted to be positioned upon the upper face of the crate bottom 1, inwardly of the upwardly turned ends 7 of the strips 2 and the crate sides 18 and 19 are provided with the vertical bracing strips 20 upon their opposite sides, which

strips are secured in position by the rivets 21 passed therethrough or by other suitable securing means. The lower ends of the strips 20 are cut-away and recesses are formed in the lower edges of the sides 18 and 19, as shown at 22 to accommodate the strips 2 upon the upper face of the bottom 1 and thus permit the lower edges of the sides 18 and 19 to rest upon the upper face of the bottom 1, as will be clearly understood by referring to the drawings. It will also be understood that inward movement of the sides 18 and 19 will be prevented by the hinged projections 8 carried by the strips 2 and also by the 15 bracing strips 15 upon the inner face of the crate ends 13 after said ends are in set up or vertical position. The strips 20 are also provided with the openings 23 adjacent their opposite ends, the purpose of which will 20 presently appear and the upper ends of the strips 20 are cut-away the same as their lower ends and the recesses 24 are formed in the upper edges of the sides 18 and 19 at the upper ends of the strips 20 to accommodate 25 the bracing strips 25 secured transversely to the under face of the crate top 26, adjacent the opposite ends of said top.

The strips 25 are secured in position by the rivets 27 or other suitable securing means 30 which also pass through bracing strips 28 upon the upper face of the crate top 26. The opposite ends of the bracing strips 25 are turned downwardly at about right angles, as shown at 29 for engagement outwardly of 35 the crate sides 18 and 19 along the upper edges thereof to prevent outward movement or spreading of the side members at their upper edges. Inward movement of the upper edges of the side members 18 and 19 is 40 prevented by the lateral projections 30 carried by the bracing strips 25 and extended to the opposite ends of the crate top 26 and then turned downwardly, as shown at 31, for engagement with the outer faces of the 45 crate ends 13 at their upper edges to prevent outward movement of said end members at their upper edges.

The bracing strips 25 and 28 are also provided with spaced openings 32 and the connecting ropes 33 are passed through the openings 32, through the openings 23 in the bracing strips of the side members 18 and 19 and through the openings 5 in the bracing strips 2 and 3 of the crate bottom 1, thus connecting the crate top and sides with the crate bottom. A ring 34 is connected with one end of each rope 33 by means of the link 35 which has its opposite ends bent around the ring 34 and the pin 36 is pivoted upon the ring 34 between the ends of the link 35 and has its free end extending across the diametrically opposite point of the ring 34. A short chain section 37 is secured to the opposite end of each rope 33 and after 65 the crate is in set up or closed position, the

ropes 33 are tightened and the chain sections 37 passed through the rings 34 and the pins 36 engaged through the proper links of said sections to securely lock the crate in closed position. It will be understood that if desired, a suitable seal may then be pasted over the rings 34 and pins 36 to prevent unauthorized parties from gaining access to the contents of the crate. 70

The bracing strips 28 are also provided 75 with lateral projections 38 opposite the projections 30 of the bracing strips 35 and rivets or other suitable securing members 39 are passed through the projections 38 and the projections 30 to securely fasten said 80 projections to the opposite faces of the crate top 26.

When it is desired to fold the crate in compact form, the end members 13 are folded upon the upper face of the bottom 1 85 while the side 18 is folded upon the lower face of said bottom and the side 19 folded upon the side 18. The top 26 is then folded upon the crate ends 13. It will thus be seen that when folded in this manner, the 90 crate will be in compact form and will require the minimum amount of space, in shipping or storing away the crates. 95

While I have shown the preferred embodiment of my invention, it will be understood that I do not wish to be limited to this specific form, as minor changes in the details of construction may be made within the scope of the appended claims without departing from the spirit of my invention. 100

The ends 13 are provided with the recesses 40 in their upper edges at the upper ends of the strips 12 and 15, to accommodate the lateral projections 30 of the bracing strips 25 and thus allow the crate top 105 26 to rest flat against the upper edge of the ends and sides of the crate.

It will be understood that the bottom, top, sides and ends of the crate may be constructed of wood or any other suitable material. 110

Having thus described my invention, what I claim is:—

1. A crate comprising a bottom member having transverse reinforcing and bracing members adjacent its opposite ends, side members having transverse reinforcing and bracing members adjacent their opposite ends, a top member having transverse reinforcing and bracing members adjacent its opposite ends, a pair of end members hinged to the opposite ends of the bottom member, said reinforcing and bracing members carried by the top member having lateral projections extending to the opposite ends of 115 said top member, said side members having cut-away portions along their opposite edges to accommodate the reinforcing and bracing members carried by the bottom member 120 and top member, said end members having 125 130

cut-away portions along their upper edges to accommodate the lateral projections of the reinforcing and bracing members carried by the top member, means for connecting the bottom, top and side members, and means carried by the side members for retaining the end members in proper position.

2. A crate comprising a bottom member having transverse reinforcing strips near its opposite ends, connecting cords engaged through the reinforcing strips, side members having reinforcing strips near its opposite ends, said connecting cords being threaded through the reinforcing strips of the side members, a top member having transverse reinforcing strips, said connecting

20 cords being threaded through the transverse reinforcing strips of the top member, end members hinged to the bottom member, the reinforcing strips of the side and top members limiting inward movement of the end members, means for securing the end members in closed position, and means for connecting the opposite ends of the connecting cords.

25 In testimony whereof I hereunto affix my signature in the presence of two witnesses.

WALTER HERZFELDT.
